UNITED STATES PATENT OFFICE.

WOJCIECH SROKA, OF CHICAGO, ILLINOIS.

DESIGN FOR A SPRINKLING-CAN.

56,774.

Specification for Design.

Patented Dec. 14, 1920.

Application filed March 8, 1920. Serial No. 364,304. Term of patent 7 years.

To all whom it may concern:

Be it known that I, WOJCIECH SROKA, a citizen of Poland, residing at Chicago, in the county of Cook and State of Illinois, have invented a new, original, and ornamental Design for a Sprinkling-Can, of which the following is a specification, reference being had to the accompanying drawing, forming part thereof.

The figure is a view in perspective of a sprinkling can, showing my new design.

I claim:—

The ornamental design for a sprinkling can, as shown.

WOJCIECH SROKA.
